UNITED STATES PATENT OFFICE.

LEVI JUDGE, OF OLEAN, NEW YORK.

WOOD-WORKING MACHINE.

SPECIFICATION forming part of Letters Patent No. 392,343, dated November 6, 1888.

Application filed April 19, 1888. Serial No. 271,135. (No model.)

To all whom it may concern:

Be it known that I, LEVI JUDGE, a citizen of the United States, residing at Olean, in the county of Cattaraugus and State of New York, have invented a new and useful Improvement in Wood-Working Machines, of which the following is a specification.

My invention relates to an improvement in wood-working machines for beading and grooving the stiles of doors, sashes, and blinds; and it consists in the peculiar construction and combination of devices that will be more fully set forth hereinafter, and particularly pointed out in the claims.

15 In the accompanying drawings, Figure 1 is an elevation of the front side of a wood-working machine embodying my improvements. Fig. 2 is a top plan view of the same. Fig. 3 is a vertical longitudinal sectional view taken 20 on the line $x-x$ of Fig. 2. Fig. 4 is a similar view taken on the line $y-y$ of Fig. 2. Fig. 5 is a vertical transverse sectional view taken on the line $z-z$ of Fig. 2. Fig. 6 is a similar view taken on the line $w-w$ of Fig. 2. Fig. 7 25 is a detailed perspective view of the movable cutter-head. Fig. 8 is a similar view of the cutter-head for beading the stiles. Fig. 9 is a detail view.

30 A B represent the sides of the frame. The side A is provided on its inner side, at a suitable distance from its front end, with a vertical groove, C. On the inner side of side B, and in line with groove C, is secured a guideway, D, which is provided on its inner side 35 with a vertical groove, E. The sides of the guideway project beyond the central grooved portion thereof and form flanges F, which are screwed or bolted to the side B, as shown.

G represents a vertically movable head, 40 which is provided on opposite sides with vertical tongues that fit in the grooves C and E, and thereby enable the said head to be raised or lowered in the frame.

H represents a plate, which is arranged on 45 one side of the head on the upper side of the same, is provided near its ends with a pair of horizontal slots, I, and has at its extremities a pair of bearings, K. Screws L extend through the slots I and enter the upper side 50 of the head and serve to secure the plate H thereto and enable the same to be adjusted in

the direction of its length toward or from the proximate side A of the frame.

M represents a horizontal shaft, which is journaled in the bearings K, and is provided 55 near its center with a pulley, N. One end of the said shaft projects beyond the side A of the frame and is reduced to form a spindle, O. At the inner end of the said spindle is a collar or flange, P.

60 R represents a pair of circular heads, which are slipped on the spindle, are provided on their opposing sides with tangential grooves S, and in the said grooves are secured cutter-bits T, the outer ends of which are provided with 65 chisel-edges, and are adapted to cut grooves in the stiles for glass or panels.

U represents a washer, which is slipped on the spindle and bears against the outer head, R, and V represents a nut which is screwed 70 on the threaded outer end of the spindle and serves to clamp the cutter-bits firmly in position between the heads.

In the lower end of the head G is journaled 75 a shaft, W, which is provided with a large pulley, X, and a small pulley, Y, said pulleys being keyed to the said shaft. An endless belt, Z, connects the pulley X with the pulley N, and is thereby adapted to impart rotary motion to the shaft M and to the cutters T.

A' represents a large pulley, which is journaled on a spindle that projects outward from the side B in line with the shaft M. Rigidly secured to the inner side of this pulley, or 85 formed integrally therewith, as may be preferred, is a pinion, B'.

C' D' represent a pair of feed-shafts, which are journaled in bearings on the upper side of the frame and are arranged on opposite sides 90 of the shaft M. The said shafts are vertically movable in their bearings, and the bearings of the shaft D' are longitudinally adjustable on the upper side of the frame, the latter being provided with longitudinal slots E' to receive 95 the bolts of the bearings, so as to permit the longitudinal movement of the latter, as will be readily understood. To one end of the shaft D' is keyed a spur-wheel, F', which meshes with the pinion B', and to the similar end of the shaft C' is keyed a spur-wheel, G', which also meshes with the pinion B', said wheels F'

and G' being out of engagement with each other. The opposite ends of said shafts C' and D' are provided, respectively, with longitudinally-grooved feed-rollers H' I'.

5 K' represents a rock-shaft, which is journaled in the sides A B near the lower front corners of the same, is provided with an operating-lever, L', which extends upward therefrom, and has a pair of rock-arms, M', which 10 extend rearward therefrom and have their free ends loosely connected to the lower sides of the vertically-movable head G. By means of this arrangement of devices the head G, carrying the cutters T, may be raised or lowered by moving the lever L', as will be readily understood.

N' represents a bar, which is arranged on the inner side of the side A, has its rear end pivoted thereto, and has its projecting front 20 end free to move vertically and provided with a weight, O', which is longitudinally adjustable thereon. Link-rods P' connect the said weighted bar to the outer ends of the roller-shafts C' D', and thereby the feed-rollers may 25 be raised by moving said weighted bar upward, and the gravity of the latter keeps the said feed-rollers normally in contact with the stile or other object on which the machine is operated, as will be readily understood.

30 R' represents a curved bracket-arm, which projects outward from the side B of the frame and forms the bearing for one end of a shaft, S', the opposite end of said shaft being journaled in the bearing in the side B. A pulley, 35 T', is rigidly secured to the shaft S', and a cone-pulley, U', is also secured to the said shaft.

V' represents an endless belt, which connects the pulleys T' and A'.

40 W' represents a lever, which is fulcrumed on the side B of the machine, and is provided with a pulley, X', which is adapted to bear against the endless belt V'. Said lever and said pulley form a belt-tightener, which is 45 adapted to be operated so as to cause the belt V' to create any desired friction on the pulleys A' and T'.

Y' represents a pair of longitudinally-adjustable standards, which are secured to the 50 floor or other suitable support at a suitable distance beyond the rear end of the frame. In bearings with which the said standards are provided is journaled a counter-shaft, Z'. Said shaft has a fast pulley, A'', a loose pulley, B'', 55 a large pulley, C'', a smaller pulley, D'', and a cone-pulley, E''. The latter is connected to the cone-pulley U' by means of an endless belt, F''. The pulley D'' is connected to the pulley Y by means of an endless belt, G'', and an end- 60 less belt (not shown) operated by an engine or other suitable motor is adapted to pass around the fast pulley A'' and to be shifted from the same onto the loose pulley B'', so as to rotate the counter-shaft, and thereby actuate the machinery or to throw the said counter-shaft and machinery out of gear.

H'' represents a transverse bar, to the ends

of which are connected a pair of bearing-blocks, I''. Said bar and said bearing-blocks are arranged on the upper side of the frame 70 at a suitable distance in rear of the roller-shaft C', and are provided with slots K'', which are arranged transversely on the upper side of the frame. Screws or bolts L'' extend through the said slots and engage the upper 75 side of the frame and adapt the bearings I'' to be adjusted laterally on the same and clamped at any desired adjustment, as will be readily understood.

M'' represents a shaft, which is journaled in 80 the bearings I'', is provided with the rigid pulley N'', and has one end projecting beyond the side A of the frame and provided with a cutter-head, O''. The said cutter-head is provided at its corners with concave grooves P'', 85 that extend in the direction of its length, and on opposite sides of the said cutter-head are secured suitable planing, beveling, grooving, or tonguing knives or cutters, R''.

S'' represents an endless belt, which connects 90 the pulleys C'' and N''.

From the foregoing description it will be understood that the motion of the counter-shaft may be communicated to the shafts M'', 95 M, C', and D' at the will of the operator, so as to cause the said shafts M' and M to rotate at a high rate of speed and the roller-shafts C' and D' to rotate at a slow rate of speed.

T'' represents a fender, which is secured to the upper side of the frame and is arranged 100 over the cutters T, and is adapted to prevent the dust and shavings made by the said cutter from flying into the face of the operator.

U'' represents a standard or knee, which is arranged on the upper side of the frame in 105 rear of the shaft M'', and is provided with longitudinal vertical slots V'', through which extend bolts or screws W'', that enter the upper side of the frame, and thereby adapt the knee or standard to be moved longitudinally on the 110 frame and secured at any desired adjustment.

X'' represents a curved shield, which is provided with a curved arm, Y'', that is pivoted to one side of the standard or knee U''. The latter has a stop-pin, Z'', projecting from the 115 outer side thereof, to support the shield when the latter is turned upward from over the cutter O'', and the said shield is provided with a projecting pivoted arm, A''', which is provided with an adjustable weight, B''', the function of 120 the said weight being to cause the free side of the shield to bear upon the upper side of the stile with any desired pressure.

C'' represents the feed-table, which is provided at its inner side with a depending longitudinal flange, D'''. From the inner side of this flange projects a trunnion, E''', which enters the vertical slot F''' in the side A and is adapted to move upward and downward therein. A stud, G''', is journaled in an opening in 130 the flange D''' and has its projecting ends squared and adapted to work in a vertical groove, H''', in the side A. A vertical screw, I'', extends downward through an opening in the

side A above the slot F³, and said screw engages the threaded opening in the trunnion E³.

K³ represents a pair of set-screws, which engage threaded openings in the flange D³ and 5 are adapted to impinge against the side A, so as to secure the feed-table at any desired vertical adjustment. The slot F³ and groove H³ serve as guides for the feed-table, and the screw I³ serves to support the feed-table and 10 to adjust the same.

L³ represents a series of pins, which project from the upper side of the feed-table, near the outer edge thereof, are secured in openings in the feed-table by means of set screws M³, and are 15 provided with springs N³, which are adapted to bear against the outer side of the stile a on which the machine is operated, so as to keep the said stile in contact with the side A of the machine and enable the same to be directed 20 in a straight line thereon.

In order to bead and groove a stile which has previously been mortised, the stile is engaged by the feed-roller and is moved by the rotary motion of the said roller, so as to carry 25 the stile past and under the cutter-heads, the lever W' being turned so as to cause the pulley X' to tighten the belt V' and enable the latter to operate on the pulley U', thereby causing the pulley A' to rotate, and consequently 30 cause the feed-rollers to operate, and thereby forming the stile longitudinally on the table. The shaft M being in rotation at a rapid rate of speed, the cutters T are rapidly revolved, and the operator, by moving the lever L' forward, causes the rock-shaft K' to 35 partly rotate, so as to lower the rock-arms M' and the head G and cause the latter to bring the revolving cutters down upon the stile, and thereby cause the same to cut a groove 40 therein.

When the stile is urged forward on the feed-table by the feed-rollers after the revolving cutters have been raised from the mortise, the cutters attached to the cutter-head O² serve to 45 bevel, groove, bead, or cut tongues upon the stile, as may be desired, according to the shape of the cutters.

A wood-working machine thus constructed is adapted not only to operate on the stiles of 50 windows, doors, and blinds, but may be employed for a great variety of other articles manufactured of wood. By reason of the feed-table being vertically adjustable on the side A of the frame the machine is adapted 55 for working wood of various sizes.

Having thus described my invention, I claim—

1. The combination of the frame, the head G, vertically movable in said frame, the plate H, movable laterally on the upper side of the head, the shaft journaled in the lower end of the head, movable vertically therewith, and having the pulleys X Y, the shaft M, jour-

naled in bearings in the plate H and having the pulley N, the cutters adapted to be connected to the projecting end of the shaft, the endless belt connecting the pulleys X N, one end of said shaft projecting beyond one side of the frame, and the counter-shaft having the pulley D² and the endless belt connecting said 70 pulley with the pulley Y, substantially as described.

2. The combination of the vertically-movable head, the plate H, movable laterally on the upper side of the head and having the 75 bearings, and the revoluble shaft M, journaled in said bearings and adapted for the attachment of the cutters, substantially as described.

3. The combination, with the frame, of the 80 vertically-adjustable feed-table on one side thereof, the laterally-adjustable bearings I² on the frame, the shaft M² in said bearings and having the pulley N² and the cutter-head, the vertically-movable head G in the frame, 85 the shaft M in the upper end of said head and having the pulley N and the cutters, the latter and the cutter-head of shaft M³ being arranged over the feed-table, the shafts C' D', journaled in vertically-movable bearings, arranged on opposite sides of shaft M, and having the feed-rolls at one end and the wheels F' G' at their opposite ends, the pulley A', having the pinion B', meshing with wheels F' G', and means, substantially as set forth, to 95 rotate the pulleys N², N, and A', substantially as described.

4. The combination of the frame, the knee or bearing U², longitudinally adjustable thereon and having the laterally-projecting arm or 100 stud Z², and the curved fender X², having arm Y², the latter being pivoted to the knee or bearing, substantially as described.

5. The combination of the frame having the vertical slot F³ and the vertical groove G³ in 105 one side, the feed-table having the trunnion E³ in slot F³, and having the depending flange D³ on its inner side bearing against the side of the frame, the studs projecting from said flange and entering groove G³, and the vertical adjusting-screw I³, swiveled in an opening in the frame at the upper end of slot F³ and having its threaded portion extending through and engaging a vertical threaded opening in the trunnion, and the set-screws K³, 115 engaging threaded openings in flange D³ and adapted to impinge on the side of the frame, substantially as described.

In testimony that I claim the foregoing as my own I have hereto affixed my signature in presence of two witnesses.

LEVI JUDGE.
